CLAIM

The ornamental design for a flange assembly for an agricultural product storage tank, substantially as shown and described.

DESCRIPTION

FIG. 1 is a front perspective view of a flange assembly for agricultural product storage tank;

FIG. 2 is a back perspective view of the flange assembly;

FIG. 3 is a front view of the flange assembly;

FIG. 4 is a back view of the flange assembly;

FIG. 5 is a right side view of the flange assembly;

FIG. 6 is a left side view of the flange assembly; and,

FIG. 7 is a bottom view of the flange assembly.

Phantom lines, where utilized, are for illustrative purposes only and form no part of the claimed design.

1 Claim, 7 Drawing Sheets
